(57) **CLAIM**

The ornamental design for a lid for beverage container, as shown and described.

DESCRIPTION

FIG. 1 is a top perspective view of a lid for beverage container according to the new design;

FIG. 2 is a left side view of the lid for beverage container shown in FIG. 1;

FIG. 3 is a right side view of the lid for beverage container shown in FIG. 1;

FIG. 4 is a front view of the lid for beverage container shown in FIG. 1;

FIG. 5 is a rear view of the lid for beverage container shown in FIG. 1;

FIG. 6 is a top view of the lid for beverage container shown in FIG. 1; and,

FIG. 7 is a bottom view of the lid for beverage container shown in FIG. 1.

The broken lines shown in the drawings are included for the purpose of illustrating environmental structure and form no part of the claimed design.
